and Co ATTORNEY

UNITED STATES PATENT OFFICE

DANIEL COPELL, OF ATLANTIC CITY, NEW JERSEY

SMOKING PIPE

Application filed May 28, 1931. Serial No. 540,781.

This invention relates to smoking instruments and has for the primary object, the provision of means removable from the stem or neck of the smoking instrument for collecting saliva and tobacco juices and to prevent the reentrance thereof into the bores of the smoking instrument and the mouthpiece thereof, thus obviating the discharge of such matter into the mouth of the smoker and permits the device to be maintained in a highly sanitary condition due to the ease in which it may be removed, cleaned and replaced for further use.

Another object of this invention is the provision of a collecting receptacle arranged in the stem or neck of the smoking instrument and having nipples in communication with the bores of the stem or neck and the mouthpiece and arranged concentrically of the end walls and spaced from the other walls thereof, so that the saliva and tobacco juices can readily enter the receptacle and be prevented from re-entering the bores, thereby maintaining the smoking instrument comparatively dry and free of foreign matter and the deliverance to the mouth of the smoker disagreeable tastes.

A further object of this invention is the provision of a removable cover for the receptacle whereby the latter may be easily cleansed of foreign matter and provides means to permit an absorbing cartridge to be placed in the receptacle should the employment of such be desirable.

A still further object of this invention is the provision of an attachment for smoking pipes or instruments which shall be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illus-

trating a smoking instrument constructed in accordance with my invention.

Figure 2 is a sectional view illustrating the bowl and the stem or neck of a pipe constructed to receive my invention.

Figure 3 is a vertical sectional view illustrating my invention applied to the mouthpiece of a smoking pipe with the cover in an opened position.

Figure 4 is a perspective view illustrating the collecting receptacle with the cover in opened position and illustrating a modification of the arrangement of the nipples.

Figure 5 is a similar view illustrating another modification of my invention wherein the cover is shown hinged to one of the side walls of the receptacle.

Figure 6 is a sectional view illustrating the form of receptacle shown in Figure 4 positioned in the neck or stem of the pipe.

Referring in detail to the drawing, the numeral 1 indicates a smoking pipe including a bowl 2 having formed integral therewith the neck or stem 3 and which is bored to form a chamber 4 and a passage 5 communicating the chamber 4 with the bowl 2.

A mouthpiece 6 is provided with a bore 7 communicating with a screw-threaded socket 8 at one end thereof to receive my invention.

A collecting receptacle 9 has one side fully opened and closed by a hinged cover 10. As shown in Figures 1 and 3, the cover 10 is hinged to one of the end walls of the receptacle and is adapted when in a closed position to have tight frictional contact with the other walls of the receptacle. A screw threaded plug 11 is formed integral with one of the end walls of the receptacle 9 and is screw threaded for threaded connection with the socket 8 of the mouthpiece 6 and is provided with a bore 12 communicating with the bore 13 of a nipple 14 formed integral with said end wall and arranged concentrically thereof and spaced from the other walls of the receptacle. A nipple 15 is carried by the other end wall of the receptacle and arranged concentrically thereof and in alignment with the nipple 14 and extends outwardly of the receptacle and is tapered to fit within the bore 5 of the smoking pipe

when the receptacle 9 is positioned in the chamber 4, thus it will be seen that the saliva and tobacco juices may enter and collect within the receptacle 9 either from the bore 7 of the mouthpiece 6 or the bore 5 leading to the bowl thus keeping the latter comparatively dry, so that the tobacco will not become moist and rendered distasteful or strong. During the use of the device the foreign matter collected within the receptacle 9 is prevented from re-entering the bores 5 and 7 due to the arrangement of the nipples 13 and 15 and after use over a period of time, the receptacle can be withdrawn from the chamber 4 and the cover 10 opened to permit the removal of the collected foreign matter.

If desired a cartridge of absorbent material may be placed within the receptacle 9 when the cover 10 is in an opened position.

Referring to my modified form of invention as shown in Figures 4 and 6, the receptacle 16 is constructed similar to the receptacle 9 and has a hinged cover 17 for closing the opened side thereof and the cover is provided with marginal flanges 18 adapted to have frictional contact with the walls of the receptacle when in a closed position for the purpose of sealing the receptacle.

A nipple 19 is formed integral with one of the end walls and is located concentrically thereof and the bore of said nipple aligns with an opening in the mouthpiece while the other end wall of the receptacle carries a nipple 20 similar in construction to the nipple 15 and is located concentrically of the respective end wall and in alignment with the nipple 19.

The nipple 20 is removable from the receptacle or the respective end wall thereof.

The smoking pipe 21 has a chamber 22 formed in the neck or stem 23 thereof which opens outwardly through one side wall of said neck to permit the casing 16 to be positioned in and removed from the chamber 22 when desired. The neck or stem 23 is provided with a bore 24 in communication with the bowl of the smoking pipe 21 and also a bore 25 communicating with the nipple 19 and the bore 26 of a mouthpiece 27. The mouthpiece being of the plug type fits within a socket formed within the end of the stem.

The nipple 20 enters the bore 24 while the cover 17 is adapted to close the receptacle and it also provides a closure for the chamber 22 and may be ornamented in any suitable way or the owner's initials may be engraved or otherwise applied thereto so as to give the device an attractive appearance.

When it is desired to clean the receptacle 16 it is only necessary to swing the cover 17 into an open position as shown in Figure 6 and the receptacle is maintained within the chamber 22 by having frictional contact with the walls thereof and if for some reason it is desired the receptacle 16 can be entirely removed from the chamber 22.

As shown in Figure 5 the receptacle 28 is similar in construction to the receptacle 16 except that the cover 29 is hinged to the edge of one of the side walls by a pair of hinges 30.

From the foregoing description taken in connection with the accompanying drawing, it is to be noted that a very practical and efficient attachment has been provided which may be easily and conveniently installed in a conventional type of smoking pipe or other smoking instrument and will efficiently collect foreign matter, such as saliva and tobacco juices and prevent the re-entrance thereof either to the bowl of the smoking instrument or into the bore of the mouthpiece. Further it is to be noted that the device or attachment can be easily cleansed and thereby maintained in a highly sanitary condition.

While I have shown and described the preferred embodiment of my invention, it will be understood that minor changes in construction, combination and arrangement of parts may be made without departing from the spirit and scope of my invention, as claimed.

Having thus described my invention, what I claim is:

1. A smoking instrument including a neck having a bore and a chamber in communication therewith, a mouthpiece associated with the neck and having a bore, a receptacle in said chamber, nipples carried by the end walls of the receptacle and arranged concentrically of said walls and in communication with the bores, said receptacle having a doorway, and a removable door for said doorway.

2. A smoking instrument including a neck having a bore and a chamber in communication therewith, a mouthpiece associated with the neck and having a bore, a receptacle in said chamber, nipples carried by the end walls of the receptacle and arranged concentrically of said walls and in communication with the bores, said receptacle having a doorway, and a door hinged to the receptacle for closing the doorway.

3. A smoking instrument including a neck having a bore and a chamber in communication therewith and opening outwardly through the end of said neck, a collecting receptacle received in said chamber and having a doorway, a door for closing said doorway, a nipple carried by one of the end walls of the receptacle and received in the bore of the neck and located concentrically of said end wall, a second nipple carried by the other end wall of the receptacle and located concentrically thereof and in alignment with the first named nipple, said last named end wall having an opening communicating with the second named nipple, a screw threaded plug formed integral with the last named end wall and having a bore in communication with the opening, and a mouthpiece having a bore threaded to the plug.

4. A smoking instrument including a neck having a bore and a chamber in communication therewith and opening through one side of the neck, a mouthpiece having a bore associated with the neck, a collecting receptacle in said chamber, nipples carried by the end walls of the receptacle and located concentrically of said walls and one of said nipples in communication with the bore of the neck 5 adjacent to the bore of the mouthpiece, and 10 a hinged door for the receptacle.

In testimony whereof I affix my signature.
DANIEL COPELL.
